COMMERCIAL MAILING FORM

John A. Holden, Baltimore, Md.

Application October 13, 1936, Serial No. 105,360

4 Claims. (Cl. 283—1)

My invention relates to a mailing sheet that may be made in large quantities, with small variation in message and that may be sent for a minimum of postage. The sheet is particularly adapted for use as a collection letter. Collection messages may not be sent by open mail because of postal regulations, and the usual letter not only involves a high postage rate but also a very considerable clerical handling in preparation for mailing. In this invention the sheets may be made up in large quantities, ready sealed, and need only the address and the designation of the amount due by the debtor on the closed form before it is ready for mailing. It can take the lowest rate of postage since there are a large number of identical letters and since they may be opened for postal inspection by pulling out an unsealed end flap.

The full nature of the invention will be understood from the accompanying drawings and the following description and claims.

In the drawings, Fig. 1 is a view of the inside of the unfolded sheet. Fig. 2 is a view of the sheet showing the end flaps folded over and the beginning of the making of the center fold. Fig. 3 is a view of the back of the sheet, folded ready for mailing. Fig. 4 is a view of the back of the sheet, ready for mailing, showing the address. Fig. 5 is a partial view of a modified form, showing the sheet open. Fig. 6 is a view showing the first fold of the end flap. Fig. 7 is a partial back view, showing the sheet folded and marked, for mailing. Fig. 8 is an enlarged sectional view on line 8—8 of Fig. 7. Fig. 9 is a view of the inside of a sheet bearing a slightly different message. Fig. 10 is a view of a guide that may be used in punching the holes in the proper place or places. Fig. 11 is a view of the folded sheet in the guide. Fig. 12 is an end view of the same.

In the drawings similar numerals refer to similar parts throughout the several views.

The sheet has a central panel portion 1, having an upper portion 2 and a lower portion 3, with the central horizontal folding line between. A long end flap 4 is at one side of the panel portion and shorter end flap 5 is at the other. A top sealing flap 6 is at the top of the panel portion. This flap has gum therealong.

In the preferred form the message is written on the inside of the panel portion and it is a form message that may be used for nearly all collections of the same house. The lower half of the end flap 5 has a column of characters or figures 7 thereon, in regular spacing and arranged from a high sum to a low sum. The sheet, bearing these

figures and the message on the panel portion, and the notation, or direction, on the upper half of end flap 5, is ready for folding and sealing, and this may be done on machines, at the printers.

When the credit department of the company issuing the forms receives them, they also have printed indicia 8, one or more, on the back of the lower half of the panel portion, which indicate the position of one or more of the figures of the column 7. If only one figure has corresponding indicia, the others may be located because of their systematic arrangement in the column. The clerk in the credit department first addresses the form to the debtor, then turns it over and places the ledger folio number at the top, and then spreads the end of the sealed form by squeezing it in her hands as shown in Fig. 12 and inserts a hand punch in the opening, including in the punch bite only the back section of the folded form, and punches holes 9 clear through the end flap and panel portion, at places which will indicate a selected group of figures, the addition of which will be the amount due by that particular debtor. Any other mutilation apparent adjacent the figures or characters 7 when the sheet is opened may be used instead of punching. When the form is received and opened by the debtor, it will show the amount due, the holes standing opposite the selected group of figures, as shown in Fig. 1.

A large house would have a number of accounts owing the same amount, and could get the postage rate for identical inspectable letters. There would be some letters not identical and these would require the rate for inspectable mail. The end flap 5 may be readily withdrawn for postal inspection.

The sheet should be made of opaque material or if preferred, only the portion of the panel and end flap near the figures need be opaque, so as to conceal the amount due.

In the modification shown in Figs. 5, 6, 7 and 8 instead of having figures, or other indicia 8 on the back of the panel portion holes 10 are cut through the panel portion so that when folded, each hole will indicate a particular figure of the column of characters 7. When the form is completely folded, the clerk in the credit department need now only address the form, put on the account number, and place a dot or check 11 with a stamp or other instrument in the selected group of openings. When the form is opened, these marks will be opposite the group of figures which, added, show the amount due.

In the modification shown in Figs. 9, 10, 11 and 12, the messages on the panel portion and the

upper half of end flap 5 are varied, and months 12 are used instead of figures 7. A guide 13 may be used in this, or the other forms, in place of the indicia 8 on the back of the form. The 5 form fits exactly into this guide, which has at the open end indicia 14 which correspond, exactly, in location to the location of the characters 12 on the folded form. The guide, containing the 10 form, is now squeezed, and bulged, as shown in Fig. 12, and the punch end 15 placed on the horizontal line desired as shown by the guide 13. The end of this guide also serves as an abutment for the end of the punch, to insure its proper placing in the lines indicated by the 15 guide indicia 14. After punching, the form is removed from the guide and another is inserted.

The form is designed to eliminate clerical detail, such as typing, multigraphing or mimeographing, folding, enclosing and sealing of envelopes, resulting in reduced operating costs and 20 also it is designed to reduce postage costs from one-half to two-thirds.

In addition to the above use, the characters 7 and 12 may be varied in amounts, meaning and 25 arrangement and the form may be used by commercial houses, insurance companies, public utility companies and the like.

The invention claimed is:

1. A commercial form mailing sheet comprising a horizontally centrally foldable panel portion, end flaps foldable over said panel portion and a foldable top sealing flap, a column of characters on the inside of said sheet placed in pre-arranged positions, said characters being concealed when the end flaps are folded over the panel portion, means on the outside of the folded form to indicate the position of at least one of said characters when the sheet is completely folded, whereby an operative with a knowledge 30 of the arrangement of said characters may designate one or more of the same from the back of said folded sheet and after designation, the group selected be apparent upon the unfolding of the sheet.
- 45 2. A commercial form mailing sheet comprising a horizontally centrally foldable panel portion, end flaps foldable over said panel portion and a foldable top sealing flap, a column of characters on the inside of said sheet placed in a

prearranged position adjacent one of the folding lines of one end flap with the panel portion, said characters being concealed when the end flaps are folded over the panel portion, means on the outside of said sheet and on the other side 5 of the folding line of said end flap with the panel portion, said means indicating the position of at least one of said characters when the end flaps are folded over the panel portion, whereby an operative with a knowledge of the arrangement of 10 said characters may designate one or more of the same when the end flaps are folded over, and after designation, the group selected be apparent after the unfolding of the sheet.

3. A commercial form mailing sheet comprising 15 a horizontally centrally foldable panel portion, end flaps foldable over said panel portion and a foldable top sealing flap, a column of characters on the inside of one of said end flaps placed in a prearranged position, said characters being concealed when said end flap is folded over the panel portion, means on the outside of the lower portion of the panel portion to indicate the position of at least one of said characters when the sheet is completely folded for mailing, 20 whereby an operative with a knowledge of the arrangement of said characters may designate one or more of the same when the sheet is completely folded from the outside thereof, and after designation, the group selected be apparent after 25 the unfolding of the sheet.

4. A commercial form mailing sheet comprising 30 a horizontally centrally foldable panel portion, end flaps foldable over said panel portion and a foldable top sealing flap, a column of characters on the inside of said sheet placed in a pre-arranged position, said characters being concealed when the end flaps are folded over the panel portion, indicia on the reverse side of the 35 lower portion of the panel portion to indicate the position of at least one of said characters when the sheet is completely folded for mailing, said sheets being provided with mutilations passing therethrough and placed at will as indicated by said indicia to designate selected characters from 40 the outside of said sheet when folded for mailing, said mutilations being apparent when the sheet is reopened.

JOHN A. HOLDEN.
